(57) **CLAIM**

The ornamental design for a hand-piece body for medical equipment as shown and described.

DESCRIPTION

FIG. 1 is a perspective view of a hand-piece body for medical equipment showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof; and,

FIG. 9 is an enlarged view of the area labeled 9 in FIG. 8. The alternating length broken lines in FIGS. 8 and 9 show the boundaries of the enlarged FIG. 9 view and form no part of the claimed design.

The even length broken lines show portions of the hand-piece body for medical equipment that form no part of the claimed design.
